EXTRUDED PROTECTIVE CLOSURE STRIP FOR A SLOTTED CHANNEL ELEMENT

Carl Henry La Londe, Warren, Ohio, assignor to The Youngstown Sheet and Tube Company, Mohoning, Ohio, a corporation of Ohio

Filed Dec. 26, 1967, Ser. No. 9,915

Term of patent 14 years

(Cl. D13—1)

FIG. 1 is an oblique three dimensional view of a fragmentary representative length of an extruded protective closure strip, incorporating the features of the design of this invention, and with the phantom line showing of a channel member being disclosed for illustrative purposes only.

FIG. 2 is a plan view of the strip shown in FIG. 1, and illustrating more clearly a double-line appearance at the edges of the strip width, which appearance is generated in part by the lip portions extending from the base of the generally U-shape configuration; and

FIG. 3 is a cross-sectional elevation view of the extruded closure strip of this invention illustrating the generally U-shape configuration, and the relative thicknesses and relationship of the sections forming the U.

I claim:

The ornamental design for an extruded protective closure strip for a slotted channel element, as shown and described.
